DESIGN FOR A PIN

Eleanor D. Bassett, New York, N. Y.

Application August 7, 1945, Serial No. 121,305

Term of patent 3½ years

(Cl. D45—19)

To all whom it may concern:

Be it known that I, Eleanor D. Bassett, a citizen of the United States, residing at 430 West 24th Street, in the county of New York and State of New York, have invented a new, original, and ornamental Design for a Pin, of which the following is a specification, reference being had to the accompanying drawing, forming part thereof.

I claim:

The ornamental design for a pin, as shown.

ELEANOR D. BASSETT.
